CLAIM

The ornamental design for a geological compass, as shown and described.

DESCRIPTION

FIG. 1 is a front perspective view showing the new design of the geological compass in an open configuration;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a front perspective view showing the geological compass of FIG. 1 in a closed configuration; and,
FIG. 9 is a front perspective view showing the geological compass of FIG. 1 in an open and rotated configuration.
The broken lines are provided for the purpose of illustrating environment and form no part of the claimed design.
